United States Patent Office

Des. 212,799

Patented Nov. 26, 1968

212,799

TRUCK TERMINAL

Richard H. Dyer, 313 53rd St.,
Western Springs, Ill. 60558

Filed Apr. 20, 1966, Ser. No. 1,957

Term of patent 14 years

(Cl. D13—1)

FIG. 1

FIG. 2

FIG. 3

FIG. 1 is a top plan view of my design for a truck terminal;

FIG. 2 is an elevational view taken along line 2—2 of FIG. 1;

FIG. 3 is an elevational view taken along line 3—3 of FIG. 1.

The dotted line showing of the trucks in the several views is disclosed for illustrative purposes only.

I claim:

The ornamental design for a truck terminal, substantially as shown and described.
